UNITED STATES PATENT OFFICE.

GOTTFRIED WIRRER, OF PLAINFIELD, NEW JERSEY, ASSIGNOR TO INTERNATIONAL MOTOR COMPANY, OF NEW YORK, N. Y., A CORPORATION OF DELAWARE.

APPARATUS FOR VAPORIZING HYDROCARBON FUEL.

Application filed June 29, 1923. Serial No. 648,470.

This invention relates to apparatus for the practice of the method of vaporizing fuel described and claimed broadly in the co-pending application filed by the present applicant on April 21, 1922, Serial No. 555,845 in accordance with which it is proposed to separate out from the explosive mixture the heavy ends of liquid fuel, subject such liquid fuel to a vaporizing heat at a point remote from the mixture and re-introduce such vaporized fuel back into the mixture for introduction at a predetermined temperature into an internal combustion motor. The present improvements relates particularly to the construction of the separator for effectively withdrawing the unevaporated portion of the fuel from the mixture during its passage to the inlet manifold. In accordance with the invention it is proposed to break the inlet riser and so form and dispose the open ends of the broken section within a separator chamber as to cause the mixture to take such a course as will best insure the collection of the unevaporated ends without impairing seriously the flow of the mixture. This purpose is accomplished in the preferred form by so forming the upper end of the lower section of the riser within the vaporizing chamber as to direct the employing mixture against the wall of the chamber where the unevaporated portions of fuel may collect over a large superficial area, and giving the lower end of the upper section of the riser such a form as to receive the onflowing mixture only after it has described a very circuitous course which brings it over the inner wall of the chamber to the greatest possible extent. The separator chamber communicates with a vaporizing chamber for the heavy fuel ends which is disposed at a point remote from the separator chamber and is subjected to the heat of the exhaust gases whereby the heavy ends are evaporated and returned to the mixture while the mixture itself is not subjected to the direct heat of such exhaust gases.

The evaporating chamber referred to, in accordance with the improvements may also have disposed therein an electrical heating unit, the heat of which is sufficient to volatilize hydrocarbon fuel collected therein, as for starting.

The improvements will be described with

greater particularity hereinafter in connection with the embodiment illustrated in the accompanying drawings, wherein:

Figure 1 is a view in elevation of the inlet riser, a separator chamber and exhaust pipe showing the relation of parts.

Figure 2 is a view in end elevation of the parts shown in Figure 1.

Figure 3 is a view in vertical section through the improved separator chamber and showing the relation thereto of the evaporating chamber.

Figure 4 is a view in transverse section through the separator chamber shown in Figure 3 and taken on the plane indicated by the line 4-4 of Figure 3 and looking in the direction of the arrows.

In accordance with the improved method in said copending application Serial No. 555,845 the mixture after being formed in any usual manner is passed to the inlet manifold and devices are provided for separating out the unevaporated heavy liquid fuel ends. This unevaporated portion is then withdrawn to an evaporating chamber located at a point remote from the mixture where it is subjected to the heat of exhaust gases for complete volatilization and subsequent return in volatilized form to the onflowing mixture. The present devices are designed for the purpose of effectively withdrawing the unevaporated liquid from the mixture, collecting it, transferring it to the evaporating chamber, and subsequently returning it to the onflowing mixture with minimum losses in inductive pressure and greatest effectiveness in accomplishing such withdrawal. Metering devices of any suitable form are indicated conventionally at *a*, the inlet manifold at *b*, the exhaust pipe at *c*, the separator chamber within the inlet riser at *d*, and the vaporizing chamber at *e*. The mixture formed by the metering devices *a* rises through the pipe section *f* which terminates within the separator chamber *d*. Alongside of the riser section *f* but with its lowermost end disposed generally below the level of the upper end of said section *f* is a second riser section *g* which communicates with the inlet manifold *b*. The general relationship between the sections *f*, *g*, in the preferred embodiment, is shown in Figure 4 where it appears that the upper edge

of the section f is inclined as indicated at f' and is so presented to the side wall of the separator chamber d as to direct the mixture towards the side wall and disperse it over a large superficial area. Similarly, the lower edge of the other section g is inclined as indicated at g' and turned away from the upper edge f' of the section f so that the gaseous mixture within the chamber d before flowing into the section g must circulate throughout the chamber d as indicated by the arrows in Figure 4. This relationship insures the collecting of the liquid fuel particles carried in suspension in the mixture along the walls of the chamber d and their constant separation out from the gaseous mixture which is free to flow without appreciable loss of pressure up through the section g to the inlet manifold b as a dry gas. The bottom wall d' of the chamber d is inclined as indicated in Figure 3 and may be formed at opposite sides of the riser f with drain channels d^2 by which the liquid fuel which collects in the bottom is directed to the evaporating chamber e at one side of the collecting chamber d and at a point relatively remote therefrom. The evaporating chamber e is preferably cast within the exhaust pipe c so that the heat to be exhausted will be applied directly thereto but will not be communicated to the gaseous mixture flowing through the collecting chamber d . The liquid drained into the evaporating chamber e in the manner described will be completely volatilized by the exhaust gases and drawn back into the chamber e where it will mingle with the gaseous mixture passing therethrough and so enter the riser section g . Within the chamber e may be disposed a supplementary heating unit h which may, for convenience, be of an electrical character by which, for starting, liquid collected within the chamber e may be quickly evaporated for providing the motor with an initial rich starting charge.

The scope of the invention will appear from the appended claims which are intended to cover all equivalent forms of the devices herein shown.

What I claim is:

1. In an apparatus for vaporizing hydro-carbon fuel, in combination with devices for forming a gaseous mixture and the inlet manifold, a chamber for collecting unevaporated liquid fuel ends, a riser between said first named devices and the chamber discharging thereinto, an independent riser extending from said chamber to the inlet manifold, an evaporating chamber subjected to exhaust heat and disposed at a point remote from said collecting chamber and the first named riser and means to direct the unevaporated liquid fuel in the collecting chamber into said evaporating chamber and return the volatilized gas from the evaporating chamber into the gaseous mixture in the collecting chamber.
2. In combination with inlet and exhaust manifolds and a metering device for hydro-carbon fuel, a collecting chamber, a riser extending between the metering device and said chamber and having an inclined upper edge to direct the mixture against the walls of the chamber, an independent riser extending between the chamber and the inlet manifold the lower edge of the last named riser being inclined and diametrically opposed to the inclined edge of the first named riser, a vaporizing chamber remote from the collecting chamber heated by the exhaust gases in the exhaust manifold, and a passage between the vaporizing chamber and the collecting chamber.

This specification signed this 26th day of June A. D. 1923.

GOTTFRIED WIRRER.
